UNITED STATES PATENT OFFICE.

WILBER A. CARTER, OF DETROIT, MICHIGAN.

ELECTRICAL HEATER FOR CARBURETERS.

1,285,619.

Specification of Letters Patent. Patented Nov. 26, 1918.

Application filed July 26, 1918. Serial No. 246,820.

To all whom it may concern:

Be it known that I, WILBER A. CARTER, a citizen of the United States of America, residing at Detroit, in the county of Wayne 5 and State of Michigan, have invented certain new and useful improvements in Electrical Heaters for Carbureters, of which the following is a specification, reference being had therein to the accompanying drawings.

This invention relates to electrical heaters for carbureters.

Its object is to provide means for heating a carbureter by the generation of eddy currents electrically induced in an iron core 15 surrounding the carbureter, thus achieving an economy of current as compared to a heater, the temperature of which is dependent upon the resistance of the conductor.

A further object is to provide an electrical 20 heater for carbureters that is particularly adapted for use when the car is standing still, as for example when in its garage.

In the accompanying drawings:

Figure 1 is a top view of a carbureter 25 equipped with the herein-described heater;

Fig. 2 is a view of the same in side elevation;

Fig. 3 is a vertical sectional view taken on line 3—3 of Fig. 1.

In these views the reference character A designates a carbureter, the construction of which is no feature of the present invention, and B, C and D respectively designate an air inlet, the liquid fuel supply pipe and an 30 outlet connection for the gaseous mixture.

The heater for said carbureter comprises an iron core E which has a cylindrical portion surrounding the carbureter and a bottom portion extending beneath the carbureter. Preferably a slight clearance or air 40 space is left between said core and the carbureter so that the two may be readily assembled and disassembled. Said core is supported in the described relation of the carbureter by a bracket comprising a portion F clamped between the mixture outlet and the pipe D leading to the manifold and arms G projecting from said portion F at

each side thereof and riveted to said core. A conductor H is inductively wound upon 50 the core E, preferably being embedded in insulating material J.

Dissipation of heat from the core E and from said coil to the air is reduced to a minimum by incasing said core and coil in 55 a heat insulating jacket K, preferably formed of asbestos or some asbestos product. The upper edge of the core E is formed with slots, indicated at L, respectively accommodating the pipes B, C and D. 60

In the operation of the above described heater, an alternating current being passed through the coil H results in the generation of eddy currents in the core E to heat said core. This heat is prevented from freely 65 escaping to the air by the heat insulation K and therefore is largely transmitted to the carbureter by radiation, convection and conduction.

In cold weather it is preferred to maintain 70 a constant small flow of current through the coil H when the motor vehicle carrying the carbureter is standing for any length of time, thus maintaining in the carbureter such a temperature that no difficulty will be 75 experienced in starting the motor at any time.

What I claim as my invention is:—

1. The combination with a carbureter, of a heater therefor comprising a magnetic 80 heating element surrounding the carbureter, a coil inductively wound upon said element, and a bracket supporting said heater comprising a portion engaged with the mixture outlet, and arms laterally projecting from 85 said portion and secured to said element.

2. The combination with a carbureter, of a heater comprising a magnetic heating element having a cylindrical wall surrounding the carbureter and a bottom portion extending beneath the carbureter and preventing 90 access of air to the carbureter from beneath the same, and a coil inductively wound upon said magnetic element.

In testimony whereof I affix my signature.

WILBER A. CARTER.
